(57) **CLAIM**

The ornamental design for a dinosaur-shaped food product, as shown and described.

DESCRIPTION

FIG. 1 is a perspective view showing a first embodiment of my new design, comprising a dinosaur-shaped food product; FIG. 2 is a top plan view of the dinosaur-shaped food product of FIG. 1;

FIG. 3 is a left side elevation view of the dinosaur-shaped food product of FIG. 1;

FIG. 4 is a front elevation view of the dinosaur-shaped food product of FIG. 1, the back elevation view being the mirror image thereof;

FIG. 5 is a right side elevation view of the dinosaur-shaped food product of FIG. 1;

FIG. 6 is a bottom plan view of the dinosaur-shaped food product of FIG. 1;

FIG. 7 is a perspective view showing a second embodiment of my new design, comprising a dinosaur-shaped food product;

FIG. 8 is a perspective view showing a third embodiment of my new design, comprising a dinosaur-shaped food product; FIG. 9 is a perspective view showing a fourth embodiment of my new design, comprising a dinosaur-shaped food product;

FIG. 10 is a perspective view showing a fifth embodiment of my new design, comprising a dinosaur-shaped food product; FIG. 11 is a perspective view showing a sixth embodiment of my new design, comprising a dinosaur-shaped food product;

FIG. 12 is a perspective view showing a seventh embodiment of my new design, comprising a dinosaur-shaped food product;

FIG. 13 is a perspective view showing a eighth embodiment of my new design, comprising a dinosaur-shaped food product; and,

FIG. 14 is a perspective view showing a ninth embodiment of my new design, comprising a dinosaur-shaped food product.
